UNITED STATES PATENT OFFICE.

INGOMAR FRANÇOIS ORTON, OF GALVESTON, TEXAS.

WEED-KILLING TRAIN.

1,080,158.

Specification of Letters Patent.

Patented Dec. 2, 1913.

Application filed June 4, 1913. Serial No. 771,711.

To all whom it may concern:

Be it known that I, INGOMAR F. ORTON, a citizen of the United States, residing at Galveston, in the county of Galveston and State of Texas, have invented new and useful Improvements in Weed-Killing Trains, of which the following is a specification.

The invention relates to railway car construction, and more particularly to the class 10 of sprinkling cars.

The primary object of the invention is the provision of a car wherein the interior is arranged to accommodate the workmen or crew thereof for comfort during the use 15 of the car for the sprinkling of the track bed.

Another object of the invention is the provision of a car in which a sprinkling system is arranged so that the track bed over which 20 the car travels will be sprinkled for killing vegetation or growing weeds.

A further object of the invention is the provision of a car of this character which is simple in construction, thoroughly reliable and efficient in its purpose, and also which can be constructed at a minimum expense.

With these and other objects in view, the invention consists in the construction, combination and arrangement of parts as will be hereinafter fully described, illustrated in the accompanying drawings; and pointed out in the claims hereunto appended.

In the drawings:—Figure 1 is a side elevation of a car constructed in accordance with the invention. Fig. 2 is an end elevation thereof. Fig. 3 is a horizontal sectional plan view of the same taken longitudinally through the car. Fig. 4 is a vertical sectional view on the line 4—4 of Fig. 3.

Similar reference characters indicate corresponding parts throughout the several views in the drawings.

Referring to the drawings in detail, the railway car construction comprises a car body A in the side and end walls of which are alining doorways 5 and 6 respectively, the latter being normally closed by the usual swinging doors 7, while the doorways 5 are equipped with sliding doors 8 for the closing thereof. Adjacent to the roof line 45 of the body A in the sides and ends thereof are provided ventilators 9 which may be of any well-known construction for the ventilation of the said car.

The interior of the car is constructed at

opposite ends with vestibules 10 between which are arranged a kitchen 11, dining room 12, bunk rooms 13, an engine room 14, a superintendent's room 15, and lavatories 16, the superintendent's room 15 and likewise the bunk rooms 13 being provided with any suitable folding bunks 18 which are to be occupied by the train crew, while the engine room is provided with a pipe rack 19 for receiving lengths of pipe for the holding thereof conveniently within the car. The dining room 12 and the superintendent's room 15 each are formed with a washstand 20 and an ice cooler 21 for the convenience and use of the train crew. Leading from the vestibules are aisle ways 22, the rooms being in communication with the latter through doorways 23.

It is of course to be understood that the 75 interior construction of the car body A can be varied so that the arrangement of the rooms and its equipment may be varied to suit the convenience of the train crew.

Located beneath the floor of the car body 80 A and supported in any suitable manner, preferably by the use of ordinary well-known hangers, is a system of piping which comprises a pair of longitudinally disposed pipes 24 which are arranged at opposite 85 sides of the body A and extend longitudinally thereof throughout the length of the same, each pipe 24 being provided at its ends with out-furnished elbows 25 provided with sprinkler heads 26 of any preferred type, 90 while contiguous to these elbows 25 and mounted in the pipes 24 are globe and gate valves 27 and 28, the valves 27 being designed to control the fluid supply to the sprinkler heads 26, while the valves 28 may be closed to shut off the supply to the tank 29 whereby the supply can be delivered to the sprinkler heads directly from said supply. The intake supply is delivered to the pipes 24 through inlet connections or 100 nipples 30 provided with cut-off valves 31 of any desirable type. The pipes 24 are connected with pumps 32 by means of piping 33, while the pumps 32 are connected by means of connections 34 with a feed pipe 105 presently to be described. The said pumps are operated from a fifty horse-power four-cycle engine 35 which is located within the engine room 14 and is connected up with a gasoline tank 36 for supplying fuel thereto, 110 the engine being of any ordinary well-known type and under the control of an

operator. The piping 33 is provided with suitable globe valves 37 for regulating the fluid passing therethrough, while connected with the pumps 32 are feed pipes 38 which extend longitudinally of the car body A and terminate at opposite ends thereof, the ends of the said pipes 38 being provided with suitable couplings (not shown) adapted to detachably connect with the feed pipes of adjacent cars when coupled together so that the supply from a chemical tank which is arranged in an adjacent car can be conveyed to the sprinkler heads, the pipes 38 being provided with suitable valves 40 for controlling the feed supply therethrough.

Car body A in its floor is provided with suitable trap doors 41 located at points therein to give access to the valves and the pipe system beneath the car body.

20 The gasoline tank 36 is located overhead and at one side of the water tank 29 so as to be out of the way of the train crew.

25 The pipe rack 19 is provided with shelves 42 adapted to accommodate tools or other accessories necessary for the proper working of the pumps and engine.

30 In the operation of the sprinkler the engine 35 is started for operating the pumps 32 which act upon the fluid to force the same through the pipes 12 and 38 to the sprayers 26. In this manner the roadbed will be treated for exterminating vegetation and for preventing the growth thereof so that the roadbed will be maintained in perfect condition free from weeds or other growing matter which would materially deteriorate such roadbed.

35 From the foregoing it is thought that the construction and manner of operation of the

device will be clearly understood, and therefore a more extended explanation has been omitted.

What is claimed is:

1. The combination with a car body, of pipes disposed longitudinally thereof in spaced parallel relation to each other, outward turned elbows formed at the ends of the pipes and having sprinkler heads depending therefrom, spaced pairs of valves mounted within the said pipes, nipples projecting from the pipes between the points of the valve, pumps arranged within the body and having connection with the said pipe, means for operating the pumps, and feed pipes leading from the pumps and adapted for connection with the sprinkling system of adjacent cars.

2. The combination with a car body, of pipes disposed longitudinally thereof in spaced parallel relation to each other, outward turned elbows formed at the ends of the pipes and having sprinkler heads depending therefrom, spaced pairs of valves mounted within the said pipes, nipples projecting from the pipes between the points of the valve, pumps arranged within the body and having connection with the said pipe, means for operating the pumps, feed pipes leading from the pumps and adapted for connection with the sprinkling system of adjacent cars, and a tank above the pumps and having connection with the said nipples.

In testimony whereof I affix my signature in presence of two witnesses.

INGOMAR FRANÇOIS ORTON.
